UNITED STATES PATENT OFFICE.

THOMAS MARA FELL, OF BROOKLYN, ASSIGNOR TO THE UNITED STATES
STEAM SPECIALTY COMPANY, OF NEW YORK, N. Y.

RELIEF-VALVE FOR STEAM-ENGINE CYLINDERS.

SPECIFICATION forming part of Letters Patent No. 310,935, dated January 20, 1885.

Application filed July 29, 1884. (No model.)

To all whom it may concern:

Be it known that I, THOMAS MARA FELL, a citizen of the United States, residing in the city of Brooklyn, in the county of Kings and State 5 of New York, have invented certain new and useful Improvements in Relief-Valves for Steam-Engine Cylinders; and I do hereby declare that the following is a full, clear, and exact description of the invention, which will 10 enable others skilled in the art to which it appertains to make and use the same.

The object of my invention is to provide an automatic arrangement of mechanism whereby the bad effect of over cushioning or compression of steam and water is obviated in the 15 cylinders of steam-engines.

To carry my invention into effect I arrange a set of relief pipes and chambers, and an arrangement of automatic valves connected with 20 both ends of the cylinder, as clearly illustrated in the accompanying drawings, in which similar letters refer to similar parts throughout the several views.

Figure 1 is a vertical section of the entire 25 apparatus as applied to an upright cylinder, and Fig. 2 the mode of application to a horizontal cylinder.

All the parts shown, being cylindrical in 30 form, are fully illustrated in Fig. 1, in which A is the steam-engine cylinder; B, a pressure-regulating piston-valve cylindrically turned and fitting into the chamber C, in which it moves vertically, and is further held in position by the piston-rod D, which is screwed 35 into the bottom of said piston B. The rod D is provided outside the chamber C with a hook for attaching a cord or some similar operating means, so that the valve can be lifted when desired, and on the release of the cord will 40 return to its former position. D', the seat of the valve; E, the outer or relief chamber, having an exhaust-port, F; G, the regulating screw-plug; H, the compression-chamber, in which are two valves, 1 and 2, operated by a hinged 45 joint, and both opening inward and placed at an angle so as to insure a proper setting on the seat. This chamber is placed below the relief-chamber E, but connects by the passage I. K, compression-pipes leading from both ends of

the cylinder; L, an air-cock; M, a spiral 50 spring, and N N receiving-chambers.

Mode of operation: The pipes K being connected to the compression-chamber, one by valve 1 and the other by valve 2, by being screwed into the bosses P, by opening the 55 air-cock L free vent is given to the cylinder from both ends at the same time, and which empties the chambers N, pipes K, and the chamber H. By closing the cock L and screwing down the regulating-plug G until the 60 spring M exerts a pressure on the valve-seat D' of, say, a trifle over the initial steam-pressure, the chamber H, pipes K, and chambers N will fill with water to the points marked a a. By the movement of the engine-piston any 65 excess of water now passes alternately by valves 1 and 2, the one forming a check or closing the other by its superior injection. The water, after entering the compression-chamber H, now raises the regulating piston-valve B and es- 70 capes at the exhaust-port F, which may be connected with L, and both discharges carried to some convenient point. The moment the 75 excess is passed the piston B closes by means of the power exerted by the spring M, and thereby retaining at all times the set pressure in the chamber H. In the event of overcush- 80 ioning of steam, through imperfect action or slip of the main engine-valve, or by overstroke, caused by taking up lost motion, &c., such ex- 85 cess will pass out of the cylinder and displace a portion of the water in the globes N or N, which I construct of a size of about the cube contents of the cylinder clearance. Such dis- 90 placement will then discharge a larger quantity of water by the port F; but the steam almost instantly returns to the cylinder. This action of the apparatus not only prevents straining, but economizes the steam, and may be known to occur by the cessation of the pulsations of the rod D for a few strokes of the engine, or until the water once more fills to the points a a.

The apparatus may be placed away from the engine, against the wall of the engine-house, or 95 on one side of the ship, or in any convenient place, provided the valve-seat D' is always a few inches below the points a, as shown.

The benefits to be derived by the use of this auxiliary exhaust are many. The efficiency of an engine, whether high, low pressure, or condensing, is increased, and an evenness of motion produced throughout the entire mechanism. The removal of strains and jars saves considerable repairs, and insures against delays and the possibility of personal scalding, or, worse, in the event of a cylinder-head being blown off. It insures an economical use of steam, and is therefore a fuel-saver, and while providing a constant relief for the water its construction is such that neither live nor exhaust steam can escape.

15 As a modification of my invention, especially for use on large engines, the piston B may be operated by means of a lever and weight, instead of the spring M, and separate check-valves used on the pipes K as a substitute for the valves 1 and 2.

Having fully described my invention, what I claim as especial features are as follows:

1. The combination, with a relief-valve and compression-pipes leading thereto, of check-valves for preventing the fluid being forced back through one pipe by the pressure in another, substantially as described.

2. The combination, with an engine-cylinder and a compression-pipe leading therefrom, of a relief-valve connected with said pipe, and an air-cock, also connected with said pipe and arranged below the relief-valve, so as to draw off the fluid between it and the cylinder, said cock and the seat of said relief-valve being arranged below the point where the pipe opens into the cylinder, substantially as described.

3. The combination, with an engine-cylinder,

of a compression-pipe leading therefrom, and a spring-actuated relief-valve connected with said pipe, the latter descending below its junction with the cylinder, and both it and the chamber on the cylinder side of the valve being constructed and arranged to maintain constantly a body of water between the cylinder and the relief-valve, substantially as described. 40 45

4. In steam-engines, the compression or relief pipes K, cylinder A, and the relief-valve B, operating in the manner shown, in combination with the receiving-chambers N, all operated for the purposes and in the manner as 50 substantially specified.

5. The relief-valve B, chamber E, with its exhaust F, the screw-plug G, spring M, compression-chamber H, and pipes K K, in combination with the check-valves 1 and 2, all arranged and operated in the manner and for the purposes substantially as specified. 55

6. The air-cock L, in combination with the chamber H, the relief-valve B, exhaust F, compression-pipes K, and cylinder A, for the purposes and substantially in the manner specified. 60

7. The combination, with an engine-cylinder, of a relief-valve apparatus, and the compression-pipes connecting a common chamber in said apparatus with both ends of said cylinder, said apparatus and said pipes being constructed and arranged to maintain constantly a body of water between the said apparatus and both ends of the cylinder, substantially as described. 65
